Primary Examiner — Cynthia Ramirez*Assistant Examiner* — Laura H Yu(74) *Attorney, Agent, or Firm* — Studebaker & Brackett PC(57) **CLAIM**

The ornamental design for the motor, as shown and described.

DESCRIPTION

FIG. 1 is a perspective view of the front, right, and top sides of a motor showing our new design;

FIG. 2 is a perspective view of the rear, left, and bottom sides thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of the motor is included for the purpose of illustrating portions of the motor and forms no part of the claimed design.

1 Claim, 5 Drawing Sheets(56)
